UNITED STATES PATENT OFFICE.

JOHN C. SPROULL, OF PITTSBURGH, PENNSYLVANIA.

ACCESSORY FOR TOYS.

1,078,704.

Specification of Letters Patent. Patented Nov. 18, 1913.

Application filed November 30, 1912. Serial No. 734,359.

To all whom it may concern:

Be it known that I, JOHN C. SPROULL, a citizen of the United States, residing at Pittsburgh, in the county of Allegheny and State of Pennsylvania, have invented certain new and useful Improvements in Accessories for Toys, of which the following is a specification, reference being had to the accompanying drawings.

10 This invention relates to an accessory for toys and has for its primary object to provide a device for imitating smoke issuing from the stack of a toy locomotive or engine.

15 Another object of the invention resides in the provision of a suitable base having smoke imitating means thereon and a plug attached to said base for insertion in a smoke stack.

20 Still another object of the invention is to produce an attachment or accessory for the above purpose which will materially increase the realistic appearance of engines and similar toys.

25 With the above and other objects in view as will become apparent as the description proceeds, the invention consists in certain constructions, combinations and arrangements of the parts that I shall hereinafter 30 fully describe and claim.

For a full understanding of the invention, reference is to be had to the following description and accompanying drawing, in which—

35 Figure 1 is a perspective view of the preferred embodiment of the invention, showing the same attached to the smoke stack of a toy locomotive; Fig. 2 is a section through the upper end of the smoke stack 40 with the device arranged therein; and Fig. 3 is a perspective view of a slightly modified form of the device.

Referring in detail to the drawing, 5 designates the upper end of the smoke stack 45 of a toy locomotive or engine and 6 indicates generally my improved attachment or accessory therefor.

The attachment 6 includes a base structure in the preferred form of the invention 50 formed from a plurality of wire loops 7 which are bent into irregular outline and have their extremities suitably fixed in a tapering plug 8. This plug as shown in Fig. 2 of the drawings, is adapted to be inserted into the upper end of the smoke stack 55. Upon the looped wire 7, tufts of raw

cotton indicated at 9 are adapted to be adhesively secured or attached in any other preferred manner. These cotton tufts are blackened by immersing the same in a suitable dye so that as a whole they will present the appearance of smoke issuing from the stack of the locomotive.

In Fig. 3 of the drawing, I have shown a slightly modified form of the device where- 60 in the base is constructed from card board or sheet metal indicated at 10. This base which is of irregular outline may be colored and suitably shaded on one or both of its surfaces and to the same at the proper points 65 the cotton tufts 9' are attached. This base has a plug 8' secured to one end whereby the same may be attached to the stack of the locomotive. In either form of the invention, the attaching plug may be eliminated and the base structure upon which 70 the smoke-representing tufts of cotton are mounted can be permanently attached directly to the upper end of the locomotive 75 stack.

80 From the foregoing, it is believed that the construction of the invention and the manner of its use will be fully understood.

The attachment is extremely simple, may be produced at small cost and greatly adds 85 to the realistic appearance of the toy.

It will of course be obvious that the invention may be made in many other forms, without departing from the spirit or sacrificing any of the advantages of the same, 90 and I therefore reserve the right to make such alterations therein as may be fairly within the scope of the appended claims.

Having thus described the invention, 95 what is claimed is:

1. An accessory for toy locomotives comprising a base structure, a plug to which said base structure is secured, said plug being adapted for insertion into the top of the smoke stack, and cotton tufts secured to 100 said base structure.

2. An accessory for toy locomotives comprising a base structure, a plug to which one end of the base structure is secured, said plug being adapted for insertion into the 105 top of the smoke stack, and smoke representing means mounted on the base structure.

3. An accessory for toy locomotives comprising an attaching plug for insertion in the locomotive stack, a plurality of members 110 carried by said plug, and smoke representing means carried by each of said members.

4. An accessory for toy locomotives comprising a base structure consisting of a plurality of wires, a plug in which the extremities of said wires are secured adapted for insertion into the smoke stack, and smoke representing means attached to said wires.
5. An accessory for toy locomotives comprising a base structure consisting of a plurality of wires, a plug in which the extremities of said wires are secured adapted for insertion into the smoke stack, and a plurality of cotton tufts attached to said wires.

6. An accessory for toy locomotives comprising a base structure consisting of a plurality of wire loops bent into irregular outline, a plug in which the extremities of said wires are fixed adapted for insertion into the locomotive stack, and a plurality of 20 cotton tufts attached to each of said wires.

In testimony whereof I hereunto affix my signature in the presence of two witnesses.

JOHN C. SPROULL.
